UNITED STATES PATENT OFFICE.

CHARLES F. CRAMER, OF INDIANA, PENNSYLVANIA.

STRUCTURAL SYSTEM.

1,285,051.

Specification of Letters Patent.

Patented Nov. 19, 1918.

Application filed July 20, 1918. Serial No. 245,890.

To all whom it may concern:

Be it known that I, CHARLES F. CRAMER, a citizen of the United States, residing at Indiana, in the county of Indiana and 5 State of Pennsylvania, have invented certain new and useful Improvements in Structural Systems, of which the following is a specification.

This invention relates to building construction, and particularly to a system of construction wherein reinforced concrete units are used, said units being formed in the shop and being so formed as to be adapted to be laid successively and supported by 15 walls, beams and partitions.

The general object of this invention is to provide a fireproof floor and road bed construction which may be used for bridges, if desired, or in other like circumstances, 20 which embodies units adapted to be made in the shop and placed at any season of the year without damage from freezing or heat and without the use of centering forms or temporary supports, and further to provide 25 a construction of this character which may be laid by unskilled labor, without the necessity of using bolts, rivets, screws, nails or other attaching means, which units are fireproof, vermin proof and ready for 30 plastering or placing wood floors in connection therewith when desired.

A further object is to provide a unit for constructions of this character comprising 35 an outer sheath of sheet metal, and a plastic filling, the sheath being formed of a single piece of sheet metal bent into approximate trough-like form covering the bottom, sides, and ends of the plastic filling and formed to interlock therewith.

40 A further object is to provide a unit of the character above described in which the sheath is so formed that one unit will interlock with the next adjacent unit.

A further object is to provide a unit of 45 this character in which the sheath forms a wrapper and binder for the plastic filling material and providing a bearing surface at the ends of the unit whereby they protect the ends of the concrete filling where 50 the unit rests on walls or beams, in transportation, or in handling.

A further object is to so form the sheath 5 that it will add strength to the unit and tend to conduct load stresses to the vertical sides of the trough-like sheath.

A further object is to provide a construc-

tion of this character wherein a sheath or metal form is used, each form or sheath constituting a mold so constructed that metal reinforcing members are disposed 60 within the mold, which mold or sheath may be filled with initially liquid plastic material, which when hardened has binding engagement with the sheath and embeds the reinforcing elements and holds them 65 in permanent position.

A further object in this connection is to provide reinforcing rods so constructed that they may be engaged over supporting beams or girders, or form anchors for tying the 70 units into walls.

Still another object is to provide an improved form of reinforcing bar or supporting beam, having an integral truss and preferably provided with tightening wedges 75 whereby the truss may be tightened.

Other objects will appear in the course of the following description.

My invention is illustrated in the accompanying drawings, wherein:—

80 Figure 1 is a fragmentary sectional view of a floor construction showing one form of my building unit in place;

Fig. 2 is a transverse sectional view of one form of the structural unit;

85 Fig. 3 is a sectional perspective view showing another and preferable form of the structural unit;

Fig. 4 is a fragmentary elevation of one of the forms of structural unit, showing 90 a modified form of supporting and reinforcing rod, the supporting beam and flanges being in section;

Fig. 5 is a like view to Fig. 4, showing 95 another means of connecting the structural unit to a supporting beam, the structural unit being partly broken away;

Fig. 6 is a side elevation of the form of supporting beam illustrated in Fig. 1; and

Fig. 7 is a transverse sectional view 100 through the beam shown in Fig. 6.

Referring to Figs. 1 and 2, it will be seen that the unit of this constructional system is composed of an outer sheath of sheet metal designated generally A and a filling 105 of plastic material designated B. This sheath in one form of my invention, as illustrated in Fig. 2, is trough shaped in cross section to form a bottom 10, and upwardly extending sides 11. The upper margins of 110 these sides are downwardly and inwardly turned as at 12 and perforated, as at 13.

The bottom 10 is formed with a plurality of supported. The lower portion of this supported bar is designed to be concealed by a perforations 13 so that the plastic filling B false beam 25. Preferably the concrete B will enter these perforations and interlock filled into the mold or form A extends above with the metal sheath A, providing a suff- the form as illustrated in Fig. 2, and the 75 ficiency of exposed plastic for plastering to ends of the concrete filling are cut away adhere to. Preferably tongues 14 are cut out as at 26 to pass upper flanges of rolled beams of the middle of the bottom which tongues and permit the units to be placed with the are turned upward and inward and angularly bent to engage the plastic filling. hook extending over the beam C, C' or C². 75

10 Longitudinal reinforcing bars 15 are de- Preferably, also, the longitudinal upper 75 signed to be supported within the sheath or corners of the concrete filling A are rounded form before the plastic filling is put in place so as to prevent these corners from being and to be thereby embedded within the complete unit. Other tongues 14^a may be struck 80 15 out of the sides of the form A so as to cause the form to interlock with the filling. 80

The reinforcing rods 15 are extended to the ends of the unit in one form of my construction as illustrated in Fig. 1, and then 20 bent angularly upward as at 15^a and then forward and downward to form a hook 15^b to engage over the supporting beams C or to 25 anchor in the wall W. Of course the form of this hook 15^b will depend upon the cross 30 sectional form of the beam C which supports the unit. I do not wish to be limited to the use of reinforcing rods 15 extending entirely through the unit as, under some circumstances, as illustrated in Fig. 5, I may 35 reinforce the unit by a web of reticulated material 16, supported in any suitable manner within the form or sheath and embedded within the plastic material B.

Under these circumstances, however, I use 35 a supporting hook 17 which extends downward through the unit adjacent one or both ends thereof and is provided with a washer and nut 17^b, the upper end of the hook extending laterally and then downward as at 40 17^a so as to engage over the supporting beam.

I do not wish to be limited, of course, to the particular supporting beams with which 45 these units are intended to coact. Thus, in Fig. 4, I show a supporting beam which is 50 T-shaped or I-shaped in cross section and which is designated C' and to which an angle iron 18 is riveted and upon which the bottom of the unit rests. In Fig. 5, I show a beam C² which is rectangular in cross section and to which angle irons 19 are riveted and which support the unit, the lower ends 55 of the anchoring member 17 to have nuts under the sheath.

In Fig. 1, I show another form of beam C 55 which I have especially designed for use with my unit in my improved floor system and which is illustrated in detail in Fig. 6. This consists of a bar rectangular in cross section which is initially slit as at 20 for 60 nearly its entire length to form a truss 21 which is forced downward at its middle by means of a strut 22 and wedges 23. When such a bar or supporting beam is used, the angle irons 24 are riveted to the side of the 65 bar upon which the ends of the units are

4

supported. The lower portion of this supporting bar is designed to be concealed by a false beam 25. Preferably the concrete B filled into the mold or form A extends above the form as illustrated in Fig. 2, and the 75 ends of the concrete filling are cut away as at 26 to pass upper flanges of rolled beams and permit the units to be placed with the hook extending over the beam C, C' or C². Preferably, also, the longitudinal upper 75 corners of the concrete filling A are rounded so as to prevent these corners from being broken. A strip of wood or other like material 27 is designed to be initially embedded in the concrete of each unit to form a floor 80 strip to which floor supporting beams may be nailed and to which the floor itself may be nailed.

In Figs. 1 and 3, I show what I regard as a preferable form of unit. In this case one 85 of the sides 11 of the unit, at its upper margin, is turned down as at 28, parallel to the side and is then inwardly angled as at 29. The opposite side wall 11 is outwardly and downwardly bent to form a hook 30 and 90 then the sheet metal is refolded upon itself upward and inward and then downward and inward as at 31, this downwardly and inwardly extending portion 31 being formed with openings 13^a, whereby the plastic filling 95 may interlock with this downwardly and inwardly extending flange. The concrete filling is cut away on one corner, as at 32, so as to permit the hook 30 of one unit to be disposed over the upper edge of the 100 wall 11 of the next adjacent unit, in the manner illustrated in Fig. 3. Otherwise than this the construction is the same as that previously described. In this form of my invention, the sides 11 of the sheet metal 105 form are not provided with inwardly projecting tongues 14^a as in Fig. 2, but bolts such as stove bolts 33, are disposed at intervals through the sides, and preferably disposed at the neutral axes of said sides to 110 secure a thorough binding engagement between the filling and the sheath.

It is to be noted in Fig. 3, that the hook 30 has a portion extending straight outward and downward so that when this hook is disposed over the refolded upper edge of the wall 11 of an adjacent unit, it will have a 111 tendency to draw the units together. Holes or passages may be formed vertically or horizontally through the plastic filling and 12 through the trough or form A for the passage of gas pipes, conduits, etc. These will be made in an obvious manner by forming the proper holes in the metallic form and through the concrete.

The functions of the combined form and sheath A are as follows: This sheath provides a one piece metal form or mold for the plastic filling and further forms a strong envelop for the plastic filling protecting the 1

arises of the plastic material, if brittle, the envelop being bound to the plastic material both by the tongues which extend inward into the plastic material and by the perforations in the metallic form through which the plastic material protrudes and keys. Inasmuch as the metallic form extends upward at its ends, as well as at its sides, it forms a bearing surface at the ends of the units where the units rest on walls or beams and further protects the units in transportation and handling.

In the construction illustrated in Fig. 3, the metallic sheath or form is provided with an interlocking hook 30 which holds the units together and covers the joint between the units when the units are laid touching one another. These units may be afterward covered with concrete or other plastic material, if desired. The metallic sheath when made of metal thicker than #16 gage adds strength to the unit and the tongues or bolts embedded in the plastic material tend to conduct the floor load stresses to the vertical sides of the trough.

It will be seen that with this construction, the units may be made at the shop and thoroughly hardened without regard to weather conditions. They may then be transported to the place where the building is being erected and readily put in place by unskilled labor. This construction does not need, therefore, the use of centering or temporary supports, which centering systems are relatively expensive and inasmuch as the units are without bolts, rivets, screws, nails or other detached parts, the units are fireproof and vermin-proof and when laid are ready for plastering or for the placing of wood floors. Preferably the proportions of each unit will be 16 long to 2 wide and 1 high, but it is obvious, of course, that the units may be made of any desired size. It is also obvious that many changes may be made in the details of construction and arrangement of parts, without departing from the spirit of the invention and that I do not wish to be limited to the particular manner of perforating the bottom 10 or the sides of the units, the particular form of the reinforcing beams, or elements, or to the particular position to which they are placed.

I claim:

1. A structural unit comprising an outer sheet of metal sheathing having upturned sides, one of the sides having its upper margin bent downward and inward, the opposite side having its upper margin bent downward and outward to engage over the first named side of an adjacent structural unit, and a filling of initially plastic material.

2. A structural unit comprising an outer sheet metal sheathing having upturned sides, one of the sides having its upper margin bent downward and outward to form a hook,

and then refolded upon itself and extended inward and downward, and a filling of initially plastic material interlocked with said inwardly and downwardly extending portions.

3. A structural unit comprising an outer sheet metal sheathing having upturned sides, one of said sides being formed to provide a downwardly and outwardly hook shaped portion adapted to extend over the upstanding wall of an adjacent unit, and a filling of initially plastic material extending above the upper edges of said sides, that corner of the filling opposite the wall having the hook-shaped portion being cut away to permit the engagement of the hook-shaped portion of an adjacent unit with the upstanding wall.

4. A structural unit comprising an outer sheet metal sheathing having upturned sides, one of the sides having its upper margin bent downward and inward and perforated, and a filling of initially plastic material within which said perforated portion is embedded.

5. A structural unit comprising an outer sheet metal sheathing having upturned ends and sides, one of the side walls of the sheathing being downwardly and inwardly bent and perforated, the bottom of the sheathing being perforated, and a filling of initially plastic material.

6. A structural unit having an outer sheet metal sheathing having upturned ends and sides, one of the sides at its upper margin extending downward and inward and being perforated, the bottom of the sheathing being perforated, and the sheathing being formed with inwardly projecting tongues, reinforcing bars, and a filling of initially plastic material.

7. A structural unit comprising an outer sheet metal sheathing having upturned ends and sides, one of the sides having its upper margin bent downward, the opposite side being bent downward and outward to form a hook and then re-folded upon itself and extended inward and downward and being perforated, and a filling of initially plastic material.

8. A structural unit comprising an outer sheet metal sheathing having upturned ends and sides, one of the sides at its upper margin being bent downwardly upon itself and having a laterally projecting flange, the opposite side of the sheathing being bent downward and outward to form a hook and then being rebent upon itself and extended downward and inward, the last named portion being perforated, the hook of one unit being engageable over the first named side, the sheathing being perforated at a plurality of points and being formed with inwardly projecting tongues, longitudinally extending reinforcing members, and a filling of initially plastic material engaging the first

4
named margin of the second named side and extending above said perforated margin, the opposite corner of the filling being cut away whereby to permit the hooked side of one unit to be engaged with the straight side of the next adjacent unit.

9. A structural unit comprising an outer sheet metal sheathing having upturned ends and sides, one of the sides at its upper 10 margin being bent downwardly upon itself and having a laterally projecting flange, the opposite side of the sheathing being bent downward and outward to form a hook and then being rebent upon itself and extended 15 downward and inward, the last named portion being perforated, the hook of one unit

being engageable over the first named side, the sheathing being perforated at a plurality of points and being formed with inwardly projecting tongues, longitudinally extending 20 reinforcing members, and a filling of initially plastic material engaging the first named margin of the second named side and extending above said perforated margin, the opposite corner of the filling being cut away 25 whereby to permit the hooked side of one unit to be engaged with the straight side of the next adjacent unit, and tying bolts disposed through the sides of the sheathing and embedded in said filling.

In testimony whereof I affix my signature.

CHARLES F. CRAMER.
